(57) CLAIM

The ornamental design for a group of icons for a display screen, as shown and described.

DESCRIPTION

FIG. 1 is a front view of a group of icons for a display screen showing our new design; and,

FIG. 2 is an additional front view thereof.

The broken line showings of the portion of the display screen in both figures, and of the broken line circle in FIG. 1 are for environmental purposes only and form no part of the claimed design.
